(57) **CLAIM**

The ornamental design for a wireless temperature and humidity outdoor sensor, as shown and described.

DESCRIPTION

FIG. 1 is a first perspective view of a wireless temperature and humidity outdoor sensor showing my new design;
FIG. 2 is a second perspective view thereof;
FIG. 3 is a front view thereof;
FIG. 4 is a back view thereof;
FIG. 5 is a left side view thereof;
FIG. 6 is a right side view thereof;
FIG. 7 is a top view thereof;
FIG. 8 is a bottom view thereof; and,
FIG. 9 is an enlarged view of the selected portion 9 in FIG. 1.

The broken lines shown in the drawings depict portions of the wireless temperature and humidity outdoor sensor that form no part of the claimed design.
